UNITED STATES PATENT OFFICE.

JAMES J. HINDE, OF SANDUSKY, OHIO.

BUILDING-BLOCK FOR BUILDING-WALL CONSTRUCTION.

1,142,518.

Specification of Letters Patent. Patented June 8, 1915.

Application filed February 19, 1912, Serial No. 678,626. Renewed November 11, 1914. Serial No. 871,633.

To all whom it may concern:

Be it known that I, JAMES J. HINDE, a citizen of the United States of America, residing at Sandusky, in the county of Erie and State of Ohio, have invented certain new and useful Improvements in Building-Blocks for Building-Wall Construction, of which the following is a specification, reference being had therein to the accompanying drawings.

The invention relates to building walls which are composed of hollow blocks or tiles and it is the object of the invention to provide means for more perfectly alining 15 the adjacent tiles and also for effectively bonding the same.

To this end the invention consists in the peculiar construction of a bonding block or tile which is engageable with registering 20 core openings in the main blocks or tiles and bridges the joints therebetween.

In the drawings,—Figure 1 is a perspective view of a building block or tile showing my improved construction of bonding tile 25 in engagement therewith; Fig. 2 is a horizontal section through a pair of adjacent blocks with the bonding tile in engagement therewith; Fig. 3 is a vertical central section through a pair of adjacent blocks showing 30 a slightly modified construction of bonding member. A are building blocks or tiles of any suitable and usual construction and which are provided with core openings B therein and also preferably with partitions 35 C between said openings. D is my improved bonding tile which is formed of a size to telescopically engage the core openings B and of a length to bridge the joint and to extend some distance into each of the adjacent tiles. The bonding block D is preferably formed similar in structure to the 40 main blocks, that is, it is provided with core openings E and cross partitions F so as to secure the requisite strength with lightness 45 of structure.

I preferably employ the bonding block of the construction shown in Fig. 3 of the drawings, in which one end of the block is beveled as indicated at G. This bevel edge

is arranged at the bottom and projects outward beyond the building block with which the bonding block is first engaged. Thus the adjacent building block may be readily placed in position and in engagement with the bonding block or blocks by first tilting 55 it as shown in dotted lines at H, Fig. 3. The bevel edge also facilitates the placing of the mortar in the blocks to cement the bond.

By means of my invention the building wall may be more accurately laid and with 60 less skill required on the part of the workmen than with constructions heretofore used, and also the resulting structure is much stronger and more durable.

What I claim as my invention is:

1. The combination with adjacent building blocks having registering core openings therein, of a bonding block comprising a rectangular hollow member telescopically engageable with said core openings and having a bevel or pointed end for engagement with the last laid of the adjacent building blocks.

2. The combination with adjacent hollow building blocks having registering core 75 openings therein, of a bonding block having a rectangular portion telescopically engageable with the core openings of the first laid of adjacent blocks, and a projecting end beveled or pointed on its under side for 80 engagement with the core opening of the last laid of said adjacent blocks.

3. The combination with adjacent hollow building blocks having registering core openings therein, of a bonding block comprising 85 a rectangular hollow member telescopically engageable with the core openings in said blocks and indented transversely to receive the mortar, one end of said block being beveled or pointed for easy engagement with 90 the last laid of said adjacent building blocks.

In testimony whereof I affix my signature in presence of two witnesses.

JAMES J. HINDE
